[57] CLAIM

The ornamental design for a himalayan ladakhi doll, as shown and described.

DESCRIPTION

FIG. 1 is a front elevational view of a himalayan ladakhi doll showing my new design;

FIG. 2 is a rear elevational view thereof;

FIG. 3 is a right side elevational view thereof;

FIG. 4 is the top plan view thereof;

FIG. 5 is a front elevational view of a second embodiment of a himalayan ladakhi doll;

FIG. 6 is a rear elevational view of FIG. 5;

FIG. 7 is a right side elevational view of FIG. 5;

FIG. 8 is the top plan view of FIG. 5;

FIG. 9 is an enlarged front elevational view of the boots shown in FIG. 1 and 5; shown separately for clarity of illustration; and,

FIG. 10 is a side elevational view of FIG. 9.
